UNITED STATES PATENT OFFICE

FRITZ UNGERER, OF PFORZHEIM, GERMANY

ADJUSTING DEVICE FOR PLATE STRAIGHTENING MACHINES

Application filed January 23, 1932, Serial No. 588,426, and in Germany January 31, 1931.

For straightening plates, it is known to alternately incline the upper row of straightening rollers together with the yoke and the straightening roller supporting means towards both sides of the passage direction so that the imaginary plane extending through the axes of the rows of straightening rollers form an acute angle in the passage direction, the apex of this angle being directed towards the feed side.

This arrangement has been improved in that, by changing the direction of rotation of the upper straightening rollers, the inclination of the row of straightening rollers is automatically reversed. For this purpose a pinion is driven through the intermediary of a friction clutch from one of the upper straightening rollers, said pinion engaging through the intermediary of a cam with a toothed segment oscillating the yoke. This construction has however been abandoned, as amongst other things the friction clutch between the straightening rollers and the pinion did not prove to be a continually reliable means for oscillating the heavy yoke.

Finally the one sided oscillating drive of the yoke has been replaced by a central drive in such a manner that elastic twisting of the yoke body is avoided.

This invention relates to a further improvement of this type of adjusting device.

The novelty consists in the arrangement of an accessory motor which effects the adjustment of the inclination of the rows of straightening rollers by oscillating a yoke, carrying a row of straightening rollers, whereas the turning movement of the straightening rollers is effected in known manner by the main motor.

An embodiment of the invention is illustrated by way of example in the accompanying drawings, in which:—

Fig. 1 shows the plate straightening machine in front elevation.

Fig. 2 is a side elevation of Fig. 1.

Fig. 3 is a section on line 3—3 of Fig. 1.

Fig. 4 shows in a front elevation partly in section on line 4—4 of Fig. 5 the switch mechanism after removal of the box cover.

Fig. 5 is a section of the switch mechanism taken on line 5—5 of Fig. 4.

Fig. 6 is a wiring diagram showing the circuits for the main and auxiliary or oscillating motors.

The upper and lower straightening rollers *a* and *b* respectively are mounted in the rows of journal holes *a*₁ and *b*₁. The journal holes *a*₁ are arranged in both side walls *c*₁₀ of the hollow box-shaped yoke *c* which is carried on each side by a guide roller *d*₁ journaled in a transverse element *d* (Fig. 3), said roller running on a steel race *d*₂ of the yoke *c*. The curvature of the steel race *d*₂ corresponds to an arc around a point *d*₃ situated in alignment with the centres of the journal holes *a*₁. The transverse element *d* is suspended by means of rods *d*₄ to a transverse bar *h*, which is supported on the side frames *h*₁ of the machine. On the ridge of the yoke *c* vertical guides *c*₁ are arranged on brackets *c*₂ on which the cam *c*₄ keyed on a shaft *c*₅ acts, pressing towards the right and left during the oscillating movements. The shaft *c*₅ is journaled on the under side of the transverse bar *h* and carries on one end a control lever *c*₆ keyed thereto together with a reversing switch *i* and two loose adjusting levers *c*₈ and *c*₇ which can be fixed in any desired position on an arc-shaped element *c*₈. A graduation on the element *c*₈ makes it possible to impart, by simply setting the control levers *c*₆ and *c*₇, any desired angle of inclination relative to the row of straightening rollers *b* to the yoke *c* and to the row of straightening rollers *a* journaled therein. The oscillations of the yoke *c*, which is a very heavy body in the case of large plate straightening machines, are however not transmitted directly by hand by the operator, but by a separate oscillating motor *f* through the intermediary of worm *f*₁ and a worm wheel section *f*₂ keyed on the other outer end of the cam shaft *c*₅.

The wiring diagram illustrated in Fig. 6 is so arranged that, at the commencement of the automatic adjusting of the inclination of the rows of straightening rollers by means of the oscillating motor *f*, the main motor *g*, imparting the actual rotary drive to the straightening rollers *a* and *b*, is joined to the

net, and the armature circuit of the main motor can be shorted during the inclined adjustment, at the same time cutting out resistances. The control cylinder p is illustrated in developed condition and comprises two halves each with five positions for the two directions of rotation of the straightening rollers a and b .

If the control cylinder p is turned into the position 1 of the right half, phase R is brought into connection with the middle phase S through the intermediary of the wire e_2 leading through the change-over switch i and the coil of the relay m . At the same time the switch y actuated by the relays is closed. The relay m is situated between the outer phase R and the middle phase S. The closing of the relay switch y , as R is connected to w_2 and W_1 and moreover the outer phase T is connected to U_2 and U_1 , the brake magnet g of the oscillatable motor f and this motor itself are connected to the three-phase system R S T. By removing the brake magnet g , the oscillatable motor f is liberated, so that it can immediately rotate and thus oscillate the yoke c . This oscillation ceases only at the instant the relay m drops off again, that is when the relay switch y is opened. However the relay coil must be deprived of current, and this is effected automatically in that at the instant at which the inclination of the yoke c previously adjusted with the aid of the adjusting levers c_6 and c_7 is reached, the change-over switch i fixed on the cam shaft c_3 oscillates past and under the slidable element x_1 of the adjusting lever c_6 , so that the projecting button i_1 is depressed, the circuit e_2 interrupted and the relay coil consequently cut out.

The greater the angle formed by the adjusting lever c_6 with the vertical is, the greater will be the oscillation carried out by the yoke c , as the oscillating drive effected by the motor f only ceases the instant the motor f comes to a standstill under the action of a brake weight q_1 after the opening of the relay switch y .

By further turning the control cylinder p into the positions 2 to 5, which may be effected during the adjustment of the inclination of the yoke c , continually more resistances are cut out in the armature circuit of the main motor g , the stator of which has already been joined to the net with the oscillatable motor f . When the position 5 is reached, the rotor is short-circuited and attains its maximum speed of rotation.

If the control cylinder p is turned into the position 1 of the left half of the cylinder, the phase R is brought into connection with the middle phase S through the intermediary of the wire e_1 leading through the change-over switch i and of the coil of the relay m . The switch y actuated by the relay m is thus again closed. Consequently, the relay m lies be-

tween the outer phase R and the middle phase S.

The connection of the wire e_1 to the coil of the relay m is established the instant the button i_1 is depressed by means of the slidable element x_1 and thereby the connection of the wire e_2 to the coil of the relay m is broken. The change-over switch i is therefore so constructed that, when owing to the depression of one of the buttons i_1 or i_2 the relay circuit (R S) established by the bars of one half of the control cylinder is broken, the relay circuit (R S) reestablished subsequently by the bars of the other halves of the control cylinder is closed.

The closing of the relay switch y through the wire e causes the brake magnet g of the oscillatable motor f and the motor itself to be connected to the three-phase system R S T, but this time in the opposite direction, as R is connected to U and moreover the outer phase T is connected to W_1 . The oscillation of the yoke c then commencing will terminate when the change-over switch i together with the button i_2 passes under the slidable element x_2 of the adjusting lever c_7 .

If it is desired to retain the two rows of straightening rollers a and b in a certain position, for example parallel the one to the other, for several passes of the work, the relay circuit is interrupted by opening the switch k , so that the oscillatable motor f can no longer become operative.

The parts of the change over switch i , as shown in Figs. 4 and 5, are accommodated in a box i_3 with lid i_4 . It is suspended on a lever c_5 , in the channel c_6 of which the feed wires are arranged. These wires pass through an aperture i_5 into the interior of the box and are connected to the pairs of opposite contacts i_7 by means of terminals i_6 . Each pair of contacts i_7 can be interconnected by means of the oscillatable element i_8 , for which purpose this element has a bore i_9 , in which two caps i_{10} sliding between the walls i_{11} are pressed outwardly by a spring and thus close a relay circuit the instant they come into contact with the oppositely situated contacts i_7 . The oscillatable element i_8 is hingedly connected to a further oscillatable element i_{13} mounted by means of a screw i_{12} in the box i_3 . The oscillatable element i_{13} is further suspended on a tension spring i_{15} engaging below the pivot point i_{14} , which spring determines the two extreme positions of the two oscillatable elements i_8 and i_{13} , in which positions the element i_8 always suddenly switches over, in order to prevent sparking when braking and comes into contact with an abutment i_{16} . The oscillation from one extreme position into the other is caused by the depression of the buttons i_1 and i_2 on the horns i_{17} of the oscillatable element i_8 . These buttons, as shown in Fig. 5, are mutually displaced, so that they do not lie in one and the

same oscillating plane, and consequently the button i_2 can only come into contact with the x_2 and the button i_1 with the x_1 .

5 The tilting of the yoke with the aid of the adjusting device according to the invention serves the following purpose:

As shown in Fig. 2, two rows of straightening rolls a and b are arranged superposed.

10 The journals of the upper row of rolls a are mounted in the yoke c , which can be oscillated around its longitudinal axis with the adjusting device above described. In Figs. 2 and 3 the yoke c is adjusted so that the axes 15 of the rolls a lie in a horizontal plane. The yoke c can be raised and lowered according to the thickness of the plate. The more the upper rolls a are lowered, the deeper they will engage between the rolls b . If a plate to be 20 straightened is passed between the straightening rolls when the upper and lower rows are parallel, it will be found that the plate rolls in leaving the last pair of rolls, which is caused by the pairs of rolls engaging too 25 deeply. However, it is not desired to obtain a rolled plate as the result of the straightening, but an absolutely flat straightened plate, from which the stresses have been completely removed by the treatment between the 30 straightening rolls.

It has been found that the sheet metal plate no longer has a tendency to roll on leaving the machine if the interengagement of the pairs of rolls situated on the point at which the 35 plate is delivered, is not as deep as would otherwise be necessary for obtaining a good straightening result. The disadvantage of the rolling or bending up of the edge of the plate is prevented if the yoke is inclined so 40 that the straightening rolls interengage most deeply at the point at which the plate is fed into the machine and least or not at all at the point at which the plate is delivered. Consequently, the rows of straightening rolls are 45 set at an angle to one another, so that the apex of this angle is situated at the point at which the plate is fed into the machine. The inclination of the rows of straightening rolls in the machine illustrated is attained solely by 50 oscillating or tilting the yoke with the upper row of rolls so that the upper row of rolls no longer lies in a horizontal plane. The lower row of straightening rolls is not inclined and consequently in the form of construction illustrated 55 remains horizontal.

I claim:—

1. A device for adjusting the mutual inclination of rows of straightening rollers of plate straightening machines, comprising in 60 combination with the rows of straightening rollers, a main motor adapted to rotate said straightening rollers, a yoke carrying one of said rows of rollers, and an auxiliary motor adapted to oscillate said yoke and consequently 65 the row of rollers carried by said yoke,

whilst said rows of rollers are being rotated by said main motor.

2. A device as specified in claim 1, comprising in combination with the yoke, the main motor and the auxiliary motor connected in parallel with said main motor, a control cylinder connected in parallel to said auxiliary motor adapted to simultaneously connect both of said motors to the current net, an armature of said main motor adapted to be shorted by said control cylinder during the oscillation of said yoke, and resistances adapted to be cut out by said cylinder during the shorting of said main motor. 75

3. A device as specified in claim 1, comprising in combination with the yoke and the auxiliary motor, circuits of said auxiliary motor, a magnet brake of said motor, a switch adapted to open and close said circuits and to actuate said brake, a relay adapted to actuate said switch, a change-over switch controlled by said yoke connecting in parallel said auxiliary motor to said relay adapted to automatically break said circuits after a predetermined oscillation of said yoke, and a control cylinder adapted to supply current to said change-over switch to close said first mentioned switch. 80

4. A device as specified in claim 1, comprising in combination with the yoke, the main 95 motor and the auxiliary motor, a cam adapted to oscillate said yoke, a shaft carrying said cam adapted to drive said cam, a worm gearing adapted to impart the movement of said motor to said shaft, an oscillatable arm keyed on said shaft, a relay connected up in said auxiliary motor circuit, a control cylinder divided into two halves, each half connected up in one of said circuits adapted to control said circuits, a change-over switch in said circuits 100 carried by said arm adapted to switch said relay in and out, an arc-shaped element, and 105 slideable elements adjustable on said element in the path of oscillation of said change-over switch adapted to come into contact with said reversing switch, said reversing switch adapted to close said main motor circuit opened by said control cylinder and to open said auxiliary motor circuit closed by said cylinder. 110

5. A device as specified in claim 1, comprising in combination with the main motor, the auxiliary motor and the yoke, a cam adapted to oscillate said yoke, a shaft carried by said cam, a circuit of said main motor, a circuit of said auxiliary motor, a reversing switch connected up in said circuits, 115 adjusting levers loosely mounted on said shaft, guides carried by said levers adapted to control said switch and an arc-shaped element having notches adapted to fix the position of said guides. 120

6. A device as specified in claim 1, comprising in combination with the main motor, the auxiliary motor, a circuit of said main motor, a circuit of said auxiliary motor, a 125

- reversing switch connected up in said circuits, an upper oscillating element of said switch, a lower oscillating element, a pull spring connecting said oscillating element
5 engaging said lower element below the pivot point and engaging said upper element at its pivot point, said elements forming an elbow joint, abutments arranged one on each side of said lower element and each connected in one of said circuits adapted to limit the oscillating movement of said lower oscillating element, one of said circuits being closed by said elbow joint in each extreme position.
- 10 15 7. A device as specified in claim 1, comprising in combination with the main motor and said auxiliary motor, a circuit of said main motor, a circuit of said auxiliary motor, a reversing switch connected up in said 20 circuits, a casing of said switch, opposite contacts of said circuits arranged in pairs in the walls of said casing, an oscillating element having a bore of said switch adapted to connect said contacts in pairs, two slides 25 shiftably mounted in said bore, and a spring between said slides adapted to press said slides outwards against the walls of said casing and against said pairs of contacts.
8. A device as specified in claim 1, comprising in combination with the main motor, the auxiliary motor and the oscillatable yoke, a circuit of said main motor, a circuit of said auxiliary motor, a reversing switch in said 30 circuits, an oscillating element of said switch, 35 two horns on said oscillating element, two press buttons arranged in different planes of oscillation one above each of said horns, and two guides oscillatable with said yoke one above each of said press buttons adapted to 40 depress one of said buttons during each direction of oscillation of said yoke, at each oscillating movement one of said horns adapted to raise the other of said buttons.

In testimony whereof I affix my signature.
45 FRITZ UNGERER.
